UNITED STATES PATENT OFFICE

156,958

UTENSIL RACK

Camille R. Hoeft, Los Angeles, Calif.

Application October 10, 1947, Serial No. 141,849

Term of patent 7 years

(Cl. D44—29)

To all whom it may concern:

Be it known that I, Camille R. Hoeft, a citizen of the United States, residing at Los Angeles, in the county of Los Angeles and State of California, have invented a new, original, and ornamental Design for a Utensil Rack, of which the following is a specification, reference being had to the accompanying drawing, forming part thereof.

I claim:

The ornamental design for a utensil rack, substantially as shown.

CAMILLE R. HOEFT.
